CLAIM

The ornamental design of an animal leash with spring, as shown and described.

DESCRIPTION

FIG. 1 is a front perspective view of an animal leash with spring, showing my new design.

FIG. 2 is a right side view thereof.

FIG. 3 is a left side view thereof.

FIG. 4 is a front view thereof.

FIG. 5 is a back view thereof.

FIG. 6 is a top view thereof, shown enlarged for clarity of disclosure.

FIG. 7 is a bottom view thereof, shown enlarged for clarity of disclosure; and,

FIG. 8 is another front perspective view of the leash of FIG. 1, shown exploded for clarity of disclosure.

The broken lines in the drawings depict unclaimed subject matter only and form no part of the claimed design. The animal leash with spring is shown with a symbolic break in its depth. The appearance of any portion of the article between the break lines forms no part of the claimed design.
